UNITED STATES PATENT OFFICE

ISAC N. DOREMUS, OF PATERSON, NEW JERSEY.

MACHINE FOR MAKING LEADER-HOOKS.

SPECIFICATION forming part of Letters Patent No. 251,423, dated December 27, 1881.

Application filed June 5, 1879.

To all whom it may concern:

Be it known that I, ISAC N. DOREMUS, of the city of Paterson, county of Passaic, and State of New Jersey, have invented a new and useful Improvement in Machines for Making Leader-Hooks, of which the following is a specification.

My invention relates to improvements in machines for making hooks particularly adapted for fastening in place steam, water, gas, and other pipes, eaves-troughs, &c., and has for its object the uniform and speedy manufacture of such hooks.

The invention consists in the construction of the pinching devices and the rolls, and in details of construction and combination of the several parts that will be hereinafter more fully described in the specification and pointed out in the claims and drawings.

20 In the drawings, Figure 1 is a plan view of my device. Figs. 2 and 3 are end views thereof; Figs. 4 and 5, detail views, and Fig. 6 a side view, of same.

In carrying out my invention I employ a frame or base, A, upon or to which the respective parts of my machine are attached.

The pinching device b is constructed as follows:

A bow or horseshoe shaped frame, g, is 30 adapted to slide vertically upon an upright, o, fixed to a bar projecting from one side of the base A. The frame g is actuated by the hand-lever d, pivoted on a bolt connecting the uprights o o', and having a pawl, x, taking into 35 a notch or recess in the under side of the upper part of the frame g. A seat or bar, b³, is secured in openings of the uprights o o', for the metal from which the hook-blanks are to be made to rest on.

40 e c are two opposite dies, seated at one end in boxes Z, fastened to the frame g.

e is the cutter, capable of sliding between studs or guides on standards o', and being 45 acted upon by the inner or cam end of the lever d. The cutter is elevated after the cutting by a spring, S, connecting it to the pivot-bolt of the lever d. A bow, Z', has its upper ends bearing in the dies c, and is drawn downward by a spring, f, fixed to the base A, by 50 which the dies are forcibly spread apart as the frame g descends under the pressure thereof.

From the foregoing it will be noticed that with the metal inserted through the opening in the uprights o o' upon the bar b³, its end abutting against a gage, Z³, on arm Z² of said bar b³ as the lever d is elevated the cutter will be depressed, making a cut in the metal, while the dies will be brought into forcible contact therewith, and thus raise a shoulder or protuberance, aided by the cut upon the hook-blank.

I will now describe the other features of my invention, including the finishing-rolls.

d² indicates the driving-shaft, on which there is arranged a clutch for throwing the machine 65 in and out of gear.

e' indicates the movable part of the clutch, and e² the clutch-shifter, which is pivoted to the bed A and connected at its forward end to a pin projecting from a bar, e⁷, which carries a fork, e⁸, for operating the movable part of the clutch.

h h' indicate roll-shafts, on the ends of which are arranged the rolls. The end of the upper roll-shaft, h, is journaled in a movable bearing, 75 which moves vertically on guides b' b², being operated by a rock-lever, a¹.

1, 2, and 3 represent gear-wheels on the driving-shaft d² and roll shafts h h'. (Shown in Fig. 1.)

80 e³ indicates a pin-wheel on the lower roll-shaft, h', which engages with and actuates the clutch-shifter e², causing it to operate a sliding bar, e⁷, and its fork e⁸, and thus throw the machine out of gear at the end of each revolution of the rolls. The machine is thrown in gear by the stop-catch lever f', which has its front end bent up at right angles.

85 Journalled to one of the standards of frame A is a lever, e⁹, having two bent arms, e¹⁰ e¹¹. Arm e¹⁰ projects over lever f' and arm e¹¹ over bar e⁷.

d' is the pin-wheel on the end of the driving-shaft shown in Figs. 1, 3, and 6.

C' is an arm that is attached to the rocking 95 lever a¹.

e² indicates a pawl that is secured to arm C'.

f² indicates a stop-catch, g' a guard-lever, and g² a ratchet-wheel.

g³ is a pawl on the lever g', and g⁴ a spring 100 on the same lever, to keep the pawl g³ in position on the ratchet, as shown in Fig. 2.

g^5 indicates a guard for guard-lever g' , and g^6 indicates a spring that is attached to guard-lever g' .

o^4 is a spring, attached at one end to arm e' , 5 and at the other to a block, e^8 , pressing against the pawl-arm e^x ; and o^2 is another spring pressing against the pawl-arm. The spring o^4 aids the pawl-arm e^x in turning when the other spring, o^2 , is compressed by the pawl arm when 10 operated by pin-wheel d' . The spring c^3 tends continually to throw the pawl c^2 inside of the guard h^x , and causes it to snap inward after passing guard h^x , as hereinafter stated.

The operation of forming the heel or shoulder upon the metal or hook having been described, the iron is now passed through the rolls a a^x , the bottom one having a pocket formed in it, which allows the strap part of the hook to be brought forcibly in contact with the 15 rounded form of the bottom roll, a^x , which rounds the outside of the strap part of the hook. The rolls a^2 a^3 are then substituted for the rolls a a^x and put in position on shafts h h' . The top roll, a^2 , being elongated in form, rolls 20 out and tapers the shank part of the hook. 25

The top roll is depressed and brought in contact with the iron by the rocking lever a' , the top of which enters a slot in link or toggle 70, pivoted in the fixed cross-head 73, and said 30 lever bears under said head against the movable bearing q of the top roll-shaft, h . Under this there is a powerful spring, x' , (shown in Figs. 1 and 6,) which serves to raise the top roll-shaft, h , to its horizontal position as soon 35 as the handle of the rock-lever a' is thrown to one side and the depressing action thereof is removed. The movable bearing q slides on the guide-rods b' b^2 , as shown in Fig. 3. The machine is thrown out of gear at the end of each 40 revolution of the rolls by the clutch-shifter e^2 and parts connected therewith, said shifter being pivoted on the frame A, as shown in Fig. 1. The clutch-shifter e^2 has a tapering end, that 45 engages with a pin, t , on the disk or wheel e^3 of shaft h' . When the guard-lever g' has escaped from the pin g^x of ratchet g^2 the spring g^6 suddenly contracts and draws the guard-lever down which causes pawl g^3 to engage the ratchet g^2 , and thereby turn the shaft h' far enough around 50 to force the pin t of the wheel e^3 far enough forward to remove all danger of delay in the action of the clutch-shifter e^2 . The pawl c^2 on the arm C' acts, by its engagement with pin-wheel d' , to remove the stop-catch f^2 out of 55 the way of the pin on ratchet-wheel g^2 when the machine is started, and also puts the machine in gear in the following manner: When lever a' is elevated to straighten links 70 and depress shaft h the arm C' carried thereby 60 brings pawl c^2 into a position where it will be struck by one of the pins of wheel d' on driving-shaft d^2 . When this contact is made the pin-wheel, as it revolves, causes the pawl-arm to turn on its pivot and the pawl to thus act 65 against the upturned end of lever f' , pushing said lever endwise and removing stop-catch lever f^2 from its contact with the pin on ratchet-

wheel g^2 . As lever f' is pushed endwise by the pawl its upturned end engages with arm e^{10} of lever e^9 , turns said lever, and causes the 70 arm e^{11} thereof to come into contact with a pin, e^{12} , on bar e^7 , thus sliding said bar to the left and throwing by fork e^8 the movable half of the clutch into gear with the fixed half on the driving-shaft. Spring e^4 returns levers f' f^2 75 to their normal positions, and when the clutch is shifted to stop the machine pin e^{12} returns lever e^9 . As the pawl c^2 is carried forward by pin-wheel e^3 it is forced to turn outward on a horizontal pivot of the pawl-arm, when it contacts with lever f' and arm e^{10} , as above stated, 80 and is thus removed out of the path of rotation of the pin-wheel. Guard h^x keeps the pawl in this position until lever a' is depressed, when spring c^3 causes it to snap inward. Said 85 guard also prevents pawl c^2 from being moved outward before it reaches said lever and arm. 8c

The strap part of the hooks is bent to suit the various sizes of pipes in a separate machine from my invention.

What I claim, and desire to secure by Letters Patent, is—

1. The combination of the frame g , boxes Z , dies c , cutter e , spring f , bow Z' , spring S , lever d , and pawl X , substantially as described. 95

2. The combination of the guard-lever g' , ratchet-wheel g^2 , pin g^x , spring g^6 , pawl g^3 , shaft h' , pin-wheel e^3 , pin t , and connecting mechanism for actuating the clutch, substantially as described. 100

3. The combination of pawl c^2 , pin-wheel d' , levers f' f^2 , spring e^4 , and ratchet-wheel g^2 , having pin g^x , the pawl acting against the upturned end of lever f' , pushing it endwise and removing lever f^2 from its contact with pin g^x , 105 substantially as and for the purpose set forth.

4. The combination of the frame g , boxes Z , dies c , cutter e , bow Z' , spring f , bar b^3 Z^2 , and gage Z^3 , substantially as and for the purpose set forth. 110

5. The combination of the shaft h' , ratchet-wheel g^2 , having pin g^x , spring g^6 , lever g' , pawl g^3 , pin-wheel e^3 , lever e^2 , bar e^7 , fork e^8 , and clutch e' , substantially as and for the purpose set forth. 115

6. The combination of lever a' , pawl c^2 , driving-shaft d^2 , pin-wheel d' , lever f' , having an upturned end, lever e^9 , having arms e^{10} e^{11} , bar e^7 , having pin e^{12} , fork e^8 , and clutch e' , substantially as and for the purpose set forth. 120

7. In combination with roll-shafts h h' , lever a' , having arm C', pivoted link 70, bearing q , pawl c^2 , pin-wheel d' , levers f' f^2 , and e^9 , having arms e^{10} e^{11} , bar e^7 , having pin e^{12} , pin-wheel e^3 , and clutch-shifting lever e^2 , substantially as and for the purpose set forth. 125

8. In combination, shaft h' , pin-wheel e^3 , lever e^2 , bar e^7 , having pin e^{12} , lever e^9 , having arms e^{10} e^{11} , and clutch e' , substantially as and for the purpose set forth.
